REMOVAL OF VANADIUM AND/OR SODIUM FROM PETROLEUM AND PETROLEUM PRODUCTS WITH TITANIA ON ALUMINA AND HYDROFINING

Frederick William Bertram Porter and Roy Purdy Northcott, Sunbury-on-Thames, England, assignors to The British Petroleum Company Limited

No Drawing. Application July 1, 1953,
Serial No. 365,520

Claims priority, application Great Britain July 14, 1952

3 Claims. (Cl. 196—24)

This invention relates to a process for reducing the content of vanadium and/or sodium in petroleum and petroleum products.

In the complete specification of the co-pending application Ser. No. 1,029/51 there was described a process in which the content of vanadium and/or sodium in petroleum or petroleum products is reduced by contact with bauxite in the presence or absence of hydrogen and under conditions of temperature and pressure such that vanadium and/or sodium are/is deposited on or incorporated with the bauxite. It was later discovered that the degree of vanadium and/or sodium removal under any given set of operating conditions tended to vary with bauxites of different origins.

It has now been found that the content of vanadium and/or sodium in petroleum or petroleum products can be reduced by treatment with titania on alumina.

According to the invention therefore, a process for reducing the content of vanadium and/or sodium in crude petroleum or a petroleum product comprises contacting the crude petroleum or petroleum product with a contact material consisting essentially of titania and alumina, in the presence of hydrogen and under conditions of temperature and pressure such that vanadium and/or sodium are/is deposited on the contact material.

The contact material preferably contains from 1—10% by weight of TiO_2 the remainder consisting essentially of alumina.

The preferred ranges of operating conditions for the process are as follows:

Space velocity _____ v./v./hr. 0.5 to 2.0
Temperature _____ $^{\circ}$ F. 750 to 800
Pressure _____ p. s. i. ga. 500 to 1,500
Hydrogen recycle rate _____ S. C. F./B. 1,000 to 10,000

The process of the invention is particularly adaptable as a pre-treatment process for crude petroleum or petroleum products which are to be passed to a catalytic hydrogenation process for the removal of organically combined sulphur. For example, it has been found that in the hydrofining of crude petroleum and petroleum residues using a catalyst consisting of cobalt and molybdenum oxides supported on alumina, substantial propor-

2

tions of vanadium and sodium are removed by and deposited on the catalyst and this deposition causes a steady decline in catalyst activity with hours on stream which is not wholly recovered on regeneration in the conventional manner. This invention, therefore, also includes a continuous process wherein a petroleum feedstock containing vanadium and/or sodium is first treated with titania on alumina, as above described, and is then passed to a hydrogenation zone for the removal of organically combined sulphur.

An example of the application of the invention to the treatment of a petroleum residue will now be given.

Example

Sodium and vanadium removal from Kuwait 53% volume residue.

Conditions employed:

Feedstock	Kuwait 53% vol. residue.
Space velocity	1.0 v./v./hr.
Temperature	780° F. (416° C.)
Pressure	1000 p. s. i. ga.
Hydrogen recycle rate	4000 S. C. F./B.
Direction of flow	Upward.
Duration of test	50 hours.

Results obtained: Titania on alumina (4.70 wt. TiO_2).

	Feedstock	Product (bulk over 50 hrs.)
Vanadium, p. p. m.	42	11
Sodium, p. p. m.	32	22
Sulphur, percent wt.	3.71	3.39
Specific Gravity, 60° F./60° F.	0.958	0.943

We claim:

1. A process for reducing the content of vanadium and sodium in a petroleum feedstock, comprising contacting the petroleum feedstock with a contact material consisting essentially of titania and alumina, in the presence of hydrogen at a temperature within the range 750°—800° F. and at a pressure within the range 500—1500 p. s. i. ga. whereby vanadium and sodium are deposited on the contact material.

2. A process according to claim 1, wherein the contact material contains from 1—10% by weight of TiO_2 , the remainder consisting essentially of alumina.

3. A process according to claim 1, wherein the treated feedstock is subsequently passed to a hydrogenation zone for the removal of organically combined sulphur.
